UNITED STATES PATENT OFFICE.

CHARLES J. NELSON, OF NEW YORK, N. Y., ASSIGNOR, BY MESNE ASSIGNMENTS, TO
NATIONAL CARBON COMPANY, INC., OF NEW YORK, N. Y., A CORPORATION OF
NEW YORK.

HANDLAMP.

Application filed August 1, 1925. Serial No. 47,539.

This invention relates to new and useful improvements in hand lamps and particularly to an improved circuit controlling the switch and method of mounting it on the hand lamp.

It is the object of the present invention to provide a hand lamp switch, preferably of the three-position type (i. e., one having an inoperative, a flashing and a permanent light position) which may be readily mounted on the hand lamp casing without the use of screws, rivets and the like.

With this object in view, I provide certain improvements, the nature of which will be set forth in the following detailed description of a preferred embodiment and defined in the appended claims.

In the drawings, Fig. 1 is a side elevation of my improved hand lamp; Fig. 2 an enlarged perspective view of the switch and that portion of the casing on which it is mounted; Fig. 3 is a vertical cross-section of the hand lamp with the switch in flashing position; Figs. 4 and 4^a are side and top elevations, respectively, of the spring constituting the switch; and Fig. 5 illustrates the switch in its normal inoperative position.

The hand lamp consists of a tubular metallic casing 1 open at both ends. The lower end may be closed by means of a removable cap 2 and the upper end is restricted by a flange 3 formed in the casing. The casing is preferably constructed of sheet metal and held together in a seamed joint 4. A dry battery 5, a combination reflector and lamp socket 6 and a lamp bulb 7 are enclosed by the casing. The reflector 6 is insulated from casing 1 by means of a sleeve of insulation 8 and its flaring end lies against a lens 9 which is held in place by the sleeve 8 and the flange 3. The battery 5 is pressed with its carbon electrode 10 against the base 11 of the lamp 7 by means of a coiled spring 12 which serves also to connect the zinc electrode of the battery with the casing 1.

The switch is a combination slide, actuator and contact maker and is made of one piece of flat spring. The upper end 15 of the spring constitutes the contact maker and is slightly bent back. The adjacent portion 16 of the spring slopes upward ending in a substantially level ledge 17. The ledge 17 is followed by a nose 18 formed in the

spring. Below the nose 18 the spring is 55 bent up almost at right angles into an abutment 19 which rises to a point above the plane of nose 18 where another ledge 20 is formed substantially at right angles to 19. Then the spring is curved into an actuator 60 or finger piece 21 and its lower end is doubled back at 22. The actuator 21 is somewhat wider than the upper end of the spring and shoulders 23 are projecting at 65 the meeting point of these two parts, which is in a higher plane than the ledge 20.

The device may be assembled in the following manner:

The sheet of which casing 1 is to be formed is provided with an opening 24 and 70 in alignment with this opening a band or loop 25 is punched or raised to form a sleeve. The opening 24 is just wide enough to permit passage of the narrow part of the switch 75 spring and is longer than ledge 20. The sheet is then formed into tube 1. The end 15 of the switch spring is inserted in the opening 24 and the spring end 22 placed against the casing below the loop 25. The spring is now pushed up with its end 15 80 penetrating into the casing and the end 22 sliding under the band 25. The tip of 22 is bevelled or curled up, as indicated at 26, to facilitate its passage over the opening in the casing below the loop 25. The spring is 85 advanced until it reaches the position illustrated in Fig. 5, in which the nose 18 engages the casing at the upper edge of opening 24, and the lower end 22 of the spring bridges the opening below band 25. The 90 spring is so shaped and the parts so dimensioned that the engagement between 22 and the casing tends to press the upper end 15 against the insulation 8 and away from the reflector. The spring being out of engagement with the reflector 6, the circuit of the 95 bulb 7 is interrupted and accidental vertical displacement of the spring is guarded against by the nose 18. The nose 18, together with the balance of the spring, constitutes a resilient protruding part tending to maintain the switch in an inoperative position. While the depression of actuator 21 against the resiliency of 22 will cause the 100 spring end 15 to approach reflector 6, this movement is limited by the ledge 20 which will contact with the casing below opening 24.

If it is desired to flash the light the spring is moved longitudinally by means of the actuator 21 into the position illustrated in Figs. 2 and 3. The actuator must be, however, first depressed, so that the nose 18 clear the casing. The spring end 15 is now closer to the reflector but still out of engagement therewith. If the actuator is now depressed, the ledge 20 will pass through the opening 24 until stopped by the shoulders 23 engaging the casing adjacent the opening, and the contact point 15 will be pressed into firm engagement with the reflector, completing the lamp circuit.

If it is desired permanently to light the bulb then, in the flashing position the actuator 21 is fully depressed until the abutment 19 clears the casing, and the spring is pressed upwards until its movement is stopped by the shoulders 23 engaging the casing at the upper edge of opening 24. The contact maker 15 is now wedged between the reflector 6 and the insulation 8 and the circuit is permanently closed.

In order to remove the switch from the casing, it is first pulled down to its normal position and then, by means of a sharp instrument inserted between ledge 20 and the casing 1, the spring is lifted until the abutment 19 clears the casing at the lower edge of opening 24.

What I claim is:

1. In a hand lamp, a casing, and a switching means therefor cooperating with the casing and readily entirely removable therefrom, said switching means comprising a spring having one end projecting inside the casing through an aperture therein and having the other end doubled-back on itself, the said doubled-back end being inserted in a loop integral with said casing and projecting to the outside thereof.

2. In a hand lamp, a casing, a contact means enclosed therein, a contact spring having one end cooperating with said contact

means the other end of said spring being doubled-back, and a loop integral with said casing and projecting to the outside thereof for slidably holding said doubled-back spring end.

3. In a hand lamp, a casing, a contact means within the casing, a contact spring having a control part and an end doubled-back on itself both outside of the casing and one end projecting within the casing in cooperative relation with said contact means, and a loop integral with the casing and projecting outside thereof for holding the doubled-back end under tension but slidably with respect to the casing.

4. In a hand lamp, a casing, a battery and a bulb enclosed therein, a holder for said bulb, a contact spring having one end cooperating with said holder, the other end of said spring being doubled back, and a loop integral with said casing and projecting to the outside thereof for slidably holding said doubled-back spring end.

5. In a hand lamp, a casing, a battery and a bulb enclosed therein, a holder for said bulb, a contact spring having a central part and an end doubled back on itself, both outside of the casing, and one end projecting within the casing in cooperative relation with said holder, and a loop integral with the casing and projecting outside thereof for holding the doubled-back end under tension but slidably with respect to the casing.

6. In a hand lamp, a casing, a battery and a bulb enclosed therein, a contact spring both ends of which point in the same direction, one end of said spring projecting inside the casing and cooperating with the bulb circuit, the other end extending outside the casing and a loop integral with the casing enclosing the said other end.

In testimony whereof, I have signed my name to this specification, this 30 day of July 1925.

CHARLES J. NELSON.
